UNITED STATES PATENT OFFICE.

ELMER E. ALLISON, OF HILLSIDE, PENNSYLVANIA.

WASHING-MACHINE.

SPECIFICATION forming part of Letters Patent No. 340,272, dated April 20, 1886.

Application filed December 15, 1885. Serial No. 185,730. (No model.)

To all whom it may concern:

Be it known that I, ELMER E. ALLISON, of 5
Hillside, Westmoreland county, State of Penn-
sylvania, have invented a new and useful Im-
provement in Washing-Machines, of which the
following is a full, clear, and exact description.

My invention relates to machines for wash-
ing clothes, and comprising a tub and a rubber
operating to rub and squeeze the clothes on the
bottom of the tub, the object being to provide
a simple, inexpensive, efficient, and durable
machine of this class, which will wash the
clothes with economy of time and labor.

The invention consists in certain novel fea-
tures of construction and combinations of parts
of the washing-machine, all as hereinafter
fully set forth, and particularly pointed out
in the claims.

Reference is to be had to the accompanying
drawings, forming a part of this specification, in
which similar letters of reference indicate cor-
responding parts in all the figures.

Figure 1 is a vertical longitudinal sectional
elevation of a washing-machine embodying my
improvements. Fig. 2 is a plan view thereof,
and Fig. 3 is a vertical transverse sectional
elevation thereof.

The water and clothes holding tub A of the
machine consists of opposite sides, a a , pref-
erably made of wood and with rounded lower
edges, to which the sheet-metal bottom a' is
fastened, opposite end cleats, a^2 a^2 , being se-
cured to the sides a a , to give strength and
provide a secure fastening to the tub of the
ends of its sheet-metal bottom a' . Suitable
legs, a^3 , support the tub at a convenient height,
and handles a^4 , fixed at its ends, afford a means
of carrying the machine as may be required.
A faucet, a^5 , allows the water to be drawn from
the tub.

Across the tub A and next its bottom a' are
fixed a series of cleats or slats, B, on which the
clothes to be washed are placed, and against
and over which the clothes are pressed and
rubbed by the rubber C, next described. This
rubber C is made with a series of curved bars
or plates, D, each of which is formed or pro-
vided with an upwardly-projecting lug, d ,
which passes through a slot in the lower cross-
bar, e , of the handle of the rubber, and keys
or pins d' , passed through the lugs d above the
bar e , hold the bars D firmly to the handle.

At their opposite ends the bars D are connect-
ed by cross rods or bars F, on which, between
the bars, are placed a series of spacing-washers,
 f , and whereby, when the nuts f' are applied
at opposite ends of the rods, the ends of the bars
D will be held firmly at even distances apart.

Each of the bars D is crimped or bent flat-
wise and transversely, to form a series of re-
cesses, G, alternating at opposite sides or faces
of the bar for its whole length, thereby forming
side pockets, in each of which is fastened
by two screws, h , a round flat block or disk, H,
made preferably of wood, and so that the edges
or peripheries of the disks project below the
bottom or outer edges of the bars D, to consti-
tute an upper rubbing-surface, between which
and the cross-cleats B as a lower rubbing-surface
the clothes are washed. When
the edge parts of the disks H, which had been
exposed to the clothes, are worn away, the
disks may be removed by taking out the screws
 h , and the disks then may be turned and fast-
ened again by the screws, so as to present a
new working-surface to the clothes; hence the
rubber is durable as well as effective. Bars
D, provided with the rubbing-disks H, may be
placed a greater or less distance apart for the
whole width of the rubber. The drawings
show five of such bars, each provided with
seven adjustable disks; but the number of the
bars and disks may vary as the size of the
machine and the nature of the work to be done
shall require.

In the handle cross-bar e are fixed the lower
ends of two bars, e' e' , which pass through and
are fixed to the horizontal shaft I of the rubber,
the opposite ends of which shaft project to rest
in slots i , formed partly in the opposite sides,
 a a , of the tub A and partly in lugs or plates
J, fixed to the tub. The bars e' extend up-
ward from the shaft I, and are connected at
their tops by a cross-bar, E, forming a hand-
grasp, which may be seized to operate the rub-
ber C by rocking it on its shaft I over the bot-
tom of the tub. The slots i , being open at the
top, permits the rubber to be readily lifted
from the tub, and the rubber shaft I has free
vertical play in the slots, whereby the rubber
may rise and fall to accommodate itself to a
greater or less quantity of clothes placed in
the tub.

When the clothes are placed in the tub with

a suitable quantity of water or washing-liquid, the rubber C will be rocked to rub and squeeze the clothes between the rubber disks H and the tub-cleats B, and the dirt will very quickly be removed from the clothes.

By removing the rubber C all parts of the machine may be cleaned quickly and thoroughly when the washing is finished.

Having fully described my invention, I claim

10 as new and desire to secure by Letters Patent—

1. In a washing-machine, the combination, with a tub having a concaved bottom and transverse cleats B next the bottom, and provided also with opposite vertical slot-bearings, 15 as at *i i*, substantially as specified, of a rubber, C, comprising a series of bars, D, provided with disks H and attached to a handle, and said handle journaled in the bearings *i i*, substantially as and for the purposes herein set forth.

20 2. In a washing-machine, a rocking rubber constructed with a series of bars, D, and a series of disks, H, fixed to the bars, and said bars

fixed to a handle-frame adapted to be journaled in the clothes-holding tub, substantially as herein set forth.

3. In a washing-machine, a rocking rubber constructed with a series of bars, D, crimped or bent flatwise, to form alternate recesses, G, at opposite sides, and a series of disks, H, fixed to the bars within recesses G, and said bars D, 30 fixed to a handle-frame adapted to be journaled in the clothes-holding tub, substantially as herein set forth.

4. In a washing-machine, a rocking rubber constructed with a series of bars, D, having 35 lugs *d*, keys *d'*, a series of disks, H, fixed to the bars, tie-bars F F at the ends of bars D, and a handle-frame consisting of bars *e e' E I*, said bar I forming the journals for the rubber, substantially as herein set forth.

ELMER E. ALLISON.
